UNITED STATES PATENT OFFICE.

JOSIAH PARTRIDGE, OF NEW YORK, N. Y.

DESIGN FOR DINING-CHAIRS.

Specification forming part of Design No. 11,545, dated December 23, 1879; application filed October 20, 1879.
[Term of patent 7 years.]

To all whom it may concern:

Be it known that I, JOSIAH PARTRIDGE, of the city, county, and State of New York, have originated a new and useful Design for a Dining-Chair, of which the following is a full, clear, and exact description, reference being had to the accompanying drawing, making part of this specification.

A represents the back posts of the chair, which are curved at *a* and recurved at *b*. The front edges or faces, *c*, of these posts, from their upper end to the seat *B* of the chair, (which is circular, or nearly so,) are ornamented by moldings *d*. Bridging these posts at or near their upper ends is a head-piece, *C*, in the form of an open continuous frame, with the open space *e* thereof crossed vertically by ornamental posts *f*. To the upper edge of this frame, and in line with these ornamental posts *f*, are placed balls *g*, the entire head-piece *C*, in this way formed and ornamented, resembling a coronet.

Extending from one back post, *A*, to the other, and near the seat *B* of the chair, is a bar, *D*, of plain outline, and curved to the same radius as the head-piece *C*; and extending vertically between the head-piece *C* and bar *D*, centrally between the back posts *A*, is a polygonally-shaped piece, *E*, ornamented on its face, and with an opening, *h*, formed therein.

Extending from the back posts, *A*, to the seat *B* of the chair are braces *F*, which are formed with the outlines of curves and recures, as shown in the drawing. The front edges or

faces of these braces are ornamented by moldings *i*, as is likewise ornamented the edge of the front and sides of the frame of the seat *B*. To the under side of this seat-frame is fixed an ornamental cleat, *k*, of the form and design shown in the drawing.

From the seat-frame depend the front legs, *G*. These legs are straight and cylindrical in form, and they are ornamentally turned, and united in front by two ornamental braces, *l*, the front legs being also connected to the back legs, *H*, by cylindrical braces *m*, two on each side.

What I claim as my invention is—

A design for a dining-chair in which the faces or edges of the back posts, *A*, and of the front and sides of the seat-frame *B* are ornamented with moldings, and having the head-piece of the design of an entire frame, *C*, with the space between the sides of the frame ornamented by spindles *f*, and the top edge of the frame by balls *g*, and with a polygonally shaped piece, *E*, in part filling the space enclosed by the back posts, *A*, the head-piece *C*, and the plain outlined and curved bar *D*, and with curved and recurved brace-arms *F*, ornamented on their front edge by moldings *i*, the seat-frame being also ornamented by a cleat, *k*, of irregular outline, substantially in the manner described.

JOSIAH PARTRIDGE.
